UNITED STATES PATENT OFFICE.

PHILLIP KRAKAUER, OF NEW YORK, N. Y.

SPRING-PAD.

1,247,970.

Specification of Letters Patent. Patented Nov. 27, 1917.

Application filed May 9, 1916. Serial No. 96,349.

To all whom it may concern:

Be it known that I, PHILLIP KRAKAUER, a citizen of the United States, and resident of the city of New York, in the county of 5 Kings and State of New York, have invented certain new and useful Improvements in Spring-Pads, of which the following is a specification.

This invention relates to improvements 10 in spring pads, such as spring seats, spring cushions, spring mattresses and the like.

The object of this invention is the provision of a cheap and durable spring pad which will conform to the shape of the body 15 in contact therewith without materially affecting the shape of the remainder of the pad.

A further object of this invention is the provision of a spring unit which is so constructed as to be entirely independent of the spring units in the remainder of the pad, whereby compression of any of said units does not affect the normal position of the remainder of said units.

25 A still further object of this invention is the provision of spring units which can be rapidly and cheaply made.

To attain these objects, I employ the arrangement and combination of parts shown 30 in the accompanying drawings and herein-after described and claimed.

In the drawings,

Figure 1 is a plan view of the parts comprising one of the spring units before the 35 spring portion is incased.

Fig. 2 is a plan view similar to Fig. 1 showing the spring partly incased.

Fig. 3 is an elevation of Fig. 1.

Fig. 4 is an elevation of Fig. 2.

40 Fig. 5 is a perspective view of one of the spring units and Fig. 6 is a perspective view of a spring pad, part of the outside casing being removed to show the arrangement of the spring units.

45 In the practical embodiment of my invention, I prefer to construct the spring unit 5 by first placing the coiled or helical wire spring 2 near the center of a piece of flexible material such as the square of cloth 1 50 (Fig. 1). The opposite corners 8 of said square 1 are then brought together over the top of the spring and tied into the double knot 3, sufficient tension being put upon said corners 8 to compress spring 2 55 the desired amount (Fig. 4). The remaining corners of square 1 are similarly brought

together and tied to form the complete spring unit 5.

A series of said spring units 5, each comprising the spring 2 and the casing 1 may 60 be arranged in any suitable manner in spring pad 7. One method of arrangement is shown in Fig. 6, in which the units 5 are placed side by side to form a series of rows at right angles, the outside casing 4 of pad 65 7 being then drawn over all the spring units and suitably seamed.

Connecting threads as 6 may be loosely passed through casings 1 to prevent derangement of spring units 5, though said 70 threads may be omitted without detracting from the efficacy of my invention.

It is readily seen that each of the spring units 5 is entirely independent of the remainder of said units and that depression 75 of any of said units must be by pressure substantially in the line of the axis of said unit; from which it is obvious that part of the seat, cushion or mattress in which my construction is used, which is actually 80 pressed against, will be depressed, the remainder retaining its normal position. A more perfect fit to the body is thereby obtained, insuring comfort without disturbing any other occupant of the same seat, cushion 85 or mattress.

It is also seen that depression of the spring unit simply wrinkles casing 1, which again assumes its normal position upon the release of the pressure on the spring, and 90 that two thicknesses of cloth are provided between the springs of any two units, thereby insuring long wear.

It is obvious that any piece of flexible material provided with corners for tying may 95 be substituted for the square of cloth described and shown without departing from the scope of my invention.

What I claim is:

1. In a spring pad, a spring unit comprising 100 a coiled spring and a flexible casing for said spring, the opposite corners of said casing being knotted together over one end of said spring.

2. In a spring pad, a series of independent 105 spring units each of which comprises a coiled spring and a square of cloth, the opposite corners of said square being brought together over the end of said spring and fastened together.

3. A spring unit for a spring pad, comprising 110 a coiled wire spring and a piece of

cloth, the spring resting on the piece of cloth near the center thereof and being compressed, and the opposite corners of said piece of cloth being tied together over the 5 end of the compressed spring to form a casing for said spring.

4. A spring unit for a spring pad comprising a coil spring and a piece of flexible material having corners thereon, the opposite 10 of said corners being knotted over one end of said spring for compressing said spring and for forming a casing for said spring, said casing being partly open at one end.

5. A spring pad comprising a series of 15 spring units, means for loosely connecting said units for preventing derangement of said units, and an outside casing for said units, said spring units comprising coiled wire springs, and flexible casings for each 20 of said springs formed by knotting the opposite corners of a piece of cloth together over the end of the spring.

PHILLIP KRAKAUER.
